UNITED STATES PATENT OFFICE.

WILLIAM A. LORENZ AND WILLIAM H. HONISS, OF HARTFORD, CONNECTICUT, ASSIGNEES
OF ONE-HALF TO BEECH-NUT PACKING COMPANY, OF CANAJOHARIE, NEW YORK, A
CORPORATION OF NEW YORK.

HERMETIC SEALING APPARATUS.

No. 905,894.

Specification of Letters Patent.

Patented Dec. 8, 1908.

Application filed January 26, 1905. Serial No. 242,789.

To all whom it may concern:

Be it known that we, WILLIAM A. LORENZ and WILLIAM H. HONISS, citizens of the United States, and residents of Hartford, in the county of Hartford and State of Connecticut, have invented certain new and useful improvements in Hermetic Sealing Apparatus, of which the following is a full, clear, and exact specification.

This invention relates to improvements in apparatus for exhausting and hermetically sealing jars, cans, and similar receptacles, and particularly relates to that class of apparatus in which the seal is made automatically by the readmitted atmospheric pressure after the desired degree of vacuum has been obtained. After the jars have been filled and the gaskets and caps placed in position thereon, they are put into a sealing chamber or retort, from which the air is exhausted until the desired vacuum is obtained, after which the caps are pressed down firmly upon the gaskets by mechanical devices, the air readmitted to the jars, the pressure of the mechanical devices released, and the jars removed from the sealing chamber.

It is the object of the present invention to provide means whereby a large number of jars may be easily, quickly, and simultaneously placed within or withdrawn from the exhausting chamber, without danger of breakage to the jars, or of displacement to the gaskets and caps. Also to provide means whereby the chamber may be hermetically sealed and the exhausting and sealing operations on the jars caused to take place by the action of devices within easy control of the operator and requiring but little of his time to manipulate, thus leaving him time during the exhaustion of the jar, to remove from the apparatus the set of previously sealed jars and to prepare a new set for entrance into the chamber.

A further object is to provide means whereby the sealing apparatus may be readily removed from within the chamber for examination and repairs.

Figure 1 is a side view of the jar chamber or retort and a portion of the turntable, and shows the door of the retort in its closed position. Fig. 2 is a front view of the retort with the door closed. Fig. 3 is a front view of the retort with the door open. Fig. 4 is a

side view of the retort in section on the line 55 4—8 of Fig. 3, with the valve in section on the line 9—9 of Fig. 3. Fig. 5 is a side view of the front end of the retort with the cam handle and the door in their open position. Fig. 6 is a front view of the retort without 60 the sealing carriage, in section on the line 6—6 of Fig. 4, with the door open and part of the door carriage broken away. Fig. 7 is a side view partly in section on the line 4—8 of Fig. 3, the valve being taken on the line 65 9—9 of Fig. 3. Fig. 8 shows a portion of Fig. 7 with the valve in position B. Fig. 9 is a side view of the valve in position C. Fig. 10 is an enlarged front view of two of the 70 pressing devices in section on the line 10—11 of Fig. 7, the pressers being shown in the exhausting position. Fig. 11 is a front view similar to Fig. 10 and shows the pressers in their sealing position. Fig. 12 is an end view of the turn table without trays or jars, in 75 section on the line 12—12 of Fig. 14. Fig. 13 is a top view of the turn table with a loaded slide on one side and another slide partly pushed into the retort. Fig. 14 is a side view, and Fig. 15 an end view of Fig. 13. 80 Fig. 16 is a side view of the turntable with the sealing carriage drawn out upon it. Fig. 17 is a side view of the turntable having thereon a slide and a filler with small jars on the tray; the turn table being shown in section on the line 17—17 of Fig. 12. Fig. 18 is an end view of Fig. 17 in section on the line 85 18—18.

Referring to the drawings, the exhausting chamber 26, termed for convenience the retort, is preferably a cylindrical or tubular shell 31, the inside of it forming the jar chamber 33, wherein a number of jars may be simultaneously placed for purposes of exhaustion and sealing. The retort rests upon the tie bars 28 and 29 which are supported on the side frames or legs 27. The rear end 30, of the retort is closed, while the front end may be opened to admit the jars, and is closed during exhaustion by the sliding door 100 151. Connection with a suitable exhausting pump or device, not shown, is made through the pipe 251.

In front of the retort and placed at a suitable distance therefrom is a turn table (Figs. 12 to 15) provided with two slides each one of which is capable of holding the number of jars necessary to fill the retort (in this case

sixty). The turn table is supported on the two legs 36 which are held together below by the tie rods 37, and are joined by the cross bars 38, 39, 40 and 41. The side and center bars 40 and 41 carry wheels 45 which serve as supports upon which the table may rotate. The center bar 41 is provided also with a stud 46 (Fig. 12) which serves as a pivot for the table. The turn table itself 10 comprises a bottom plate 51 to which are secured the four cross beams 52 and the four side guides 53. To the center of the bottom plate 51 between the central two of the side guides 53 is secured the swivel bearing 54 (Figs. 12 and 13) into which fits the pivot stud 46, which thus holds the table in place and serves as a support for its central section, the bottom 51 resting also on the wheels 45, so that the table is free to rotate around 15 the stud as a center. This particular construction of the supporting and swiveling devices may be modified in many other well known ways. The front cross bar 38 is provided with legs 60 in which is journaled the 20 rod 61 (Fig. 15). This rod has secured to its outer ends a pair of latches 62 and 63 having arms 64 and 65 and tails 66 and 67. These latches serve to lock the turn table when either of the slides is in alignment with 25 the jar chamber (shown in Figs. 13, 14 and 15) as one end of the turn table is then between the two latch arms 64 and 65, and is thus prevented from swinging in either direction. The latches themselves are stopped 30 in this position by the pin 68 (Fig. 14) against which the arm 64 rests.

In the inner sides of the side guides 53 are secured the bars 55 which are provided with notches 57 forming bearings for the trunnions of the rollers 56. Two slides are 40 adapted to rest upon and slide on the rollers 56 between the side guides 53 on either side of the turn table. Each of these slides is formed of a bottom plate 76 (Fig. 15), a top 45 plate 78, and an intermediate piece 77, the two plates and the piece 77 being screwed or otherwise fastened together to form an integral structure. A handle 79 secured to one end of the bottom plate 76 provides a 50 convenient means for moving the slide upon the rollers 56, the stop pins 80 (Figs. 13 and 15) limiting the movement in one direction. The edges of the top plate 78 (Figs. 14 and 15) are bent up at the sides and ends in order 55 to retain in place the jar trays which rest upon it. The jar trays are preferably made to hold twelve jars, requiring therefore five of these trays to fill each slide 78, and when the slide is filled each tray occupies a definite position 60 thereon.

Each tray is made up of a bottom plate 83 to which are secured four posts 84 joined at the top along each end of the tray by bars 85 upon which rests the separator or locator 65 86, leaving the opposite lateral sides of the

tray open. The locator is provided with holes which approximately fit the bodies of the jars, and it rests upon the bars 85 but is not fixed thereto, its ends being turned over and fitting notches 88 in the ends of the bars 70 85 so that when once placed in position it cannot move out of place until it is lifted. The jars J are placed in the tray thus formed, with their bottoms resting on the plate 83 and their bodies standing in the holes in the 75 locator 86 which thus locates each jar in a definite position on the tray, and therefore on the slide, and keeps it also from contact with its fellows. Handles 87 by which the trays may be conveniently lifted are secured 80 to each bar 85. A leveler 94 is preferably placed upon the caps G of each tray-full of jars to level and otherwise bring into place any of the caps which may be slightly disarranged before sealing. It serves also to 85 prevent subsequent tilting of the caps during the sealing operation, being preferably left upon the caps during that time.

The turn table with its supporting frame is located in front of the retort in such position that when the table is held stationary between the latch arms 64 and 65 one of the slides will be in alignment with the jar chamber of the retort 26 while the other slide will come into similar alignment when the table 95 is swung half way round so as to be again held stationary by the latch arms 64 and 65. This position is indicated in Figs. 13 and 14.

The bottom of the interior of the retort 33 is provided with a flat base 32 which supports 100 a pair of tracks 101 upon which rests the removable sealing carriage. The carriage base 102 has wheels 103 which rest on the tracks 101, and have their axles journaled in lugs 104 appurtenant to the base 102. The 105 top surface of the base 102 is level with and in alignment with the slide bottom 76 when the turn table is in its stationary position; and the slide 76 may therefore be moved upon the rollers 56 into the jar chamber 33 110 and on to the carriage base 102 where it rests during the sealing operation, the space between the base sides 105 being of suitable width to properly guide and retain the slide in place. A roller 106 supported in lugs 107 115 on the carriage base facilitates the moving of the slide. A leveling bracket 141 (Figs. 3, 7 and 8) is secured to the front of the casing 111 and serves to level any disarranged caps as the jars pass under its lower leveled side. 120 A stop 110 (Fig. 7) at the rear end of the carriage base limits the movement of the slide in that direction, and serves also to locate it in a definite position on the sealing carriage. After the conclusion of the sealing operation the slide may be moved back onto the turn table and the latter turned half way round, thus bringing the other slide into 125 position to be moved into the jar chamber.

The air pressure devices which operate to 130

seal the jars, are situated above the base 102 and supported by it on the posts 113. The casing 111 (Fig. 10) of the presser chamber 112 is provided with holes 115 through its lower wall 118, equal in number to the jars which the retort is adapted to seal at one time. Under each hole 115 is a presser cylinder 121 secured to the wall 118 and divided by the partition 122 into two open-ended chambers 123 and 124 containing pistons 130 and 131 respectively. The central part of the partition 122 forms a bearing for the piston rod 125 which has secured to its upper and lower ends the two pistons 130 and 131 respectively. A spring 132 is preferably provided to hold the pistons in their upper position as shown in Fig. 10. An air duct 135 connects the upper part of the chamber 124 above the piston 131 with the presser chamber 112, and admits to the piston 131 the same pressure which is in that chamber. A duct 136 connects the bottom of the upper chamber 123 below the piston 130 with the jar chamber 33, and insures the same pressure or vacuum below the piston 130 as exists in the jar chamber 33.

The distance between the piston 131 in its upper position, and the base 102 is such that the jars will pass under it with a little room to spare as the slide 76 moves in or out (Fig. 10). The relative location of the pistons 131 and the jars on the tray is such that each jar stands directly under a piston when the slide 76 is pushed up to the stop 110. It is the function of these presser pistons 130 and 131 to force the caps G down in a level position upon their respective jars after exhaustion has taken place and before the air is admitted to the jar chamber 33, thus preventing the entrance of any air into the inside of the jar through the closure joint before the cap is finally held in place by the atmospheric pressure. The pistons 130 and 131 are moved downward by admitting air to the presser chamber 112 before it enters the jar chamber 33, thus establishing atmospheric pressure on the upper surface of the pistons 130 and 131 while a vacuum still exists below each of them. Each pair of pistons 130 and 131 being secured together by the piston rod 125, act together on the cap G and exert upon it a pressure substantially double what it would be if the cylinder 121 contained but one piston. As the inside diameter of the presser cylinder is nearly as great as the diameter of the cap G, the pressure exerted upon the latter by the two pistons 130 and 131 is nearly double that subsequently exerted thereon by the direct action of the atmospheric pressure.

The door 151 which closes the front end of the retort during the sealing operation is of circular form, and is provided with a flat annular gasket 157 by means of which a close joint is made between the door and the mouth

end of the shell or retort 26. The door is shown in its open position in Figs. 3, 4 and 6. It is mounted to swing a short distance to and from the front of the retort, and to roll or slide aside edgewise, being supported on a traveling carriage formed of a base 153, a pair of upright posts 154 and a top bar 155 secured together. The base 153 is provided with wheels 156 which travel on the track 152. Stops 193 and 194 are secured to the track 152 at either end, and limit the travel of the carriage in both directions. The track 152 is secured to the lower front bar 176 supported on the front tie bar 28. The top of the carriage is steadied by the rollers 185 (Figs. 3 and 4) carried by the top bar 155. These rollers fit one on each side of the upper guide rail 184, which is supported by the front bar 178. The latter is secured at its ends to the uprights 177 extending from the lower front bar 176, and is secured at its middle by means of the lug 179 to the flange 34 of the front end of the retort. The door 151 is suspended from the top bar 155 by means of the links 160 (Figs. 5 and 6) which are pivoted at their upper ends to the lugs 165 by the pins 162, and at their lower ends, by means of the pins 161, to the bracket 159 secured to the top of the door 151. Springs 172 extending from the pivots 161 to studs 173 on the posts 154 tend always to draw the door away from its seat on the mouth of the retort, towards its supporting carriage. A bracket 168 is secured to the lower edge of the door 151 and is provided with a projection 169 which fits loosely between a pair of lugs 166 on the carriage base 153. A guide rail 186 is secured to the bar 176 and confines the lower part of the door 151 by means of a tongue 189 on the bottom of the lower bracket 168, the tongue 189 being in front of the guide rail 186 when the door is clear of the retort entrance. By this arrangement the door is always kept away from the front of the retort in its edgewise movements as the springs 172 act upon the top to hold it away and the guide rail 186 confines the bottom. The danger of injury to the gasket 157 by scraping it against the front of the flange 34 as the door moves to and fro is thereby avoided.

The bar 176 is provided with a pair of lugs 201 (Fig. 6) in which is journaled a shaft 202 which has secured to its inner end a grooved locking dog 203. A similar grooved dog 209 is secured to the inner end of the shaft 208 journaled in lugs 207 in the upper bar 178. The two dogs 203 and 209 are so located that when the door 151 is rolled into place in front of the retort, the tongue 189 in the lower door bracket 168 and a similar tongue 190 on the upper door bracket 159 will pass into the grooves of the two dogs 203 and 209 (Fig. 4), the lower tongue 189 being of sufficient length to allow its front end to enter its

groove before its rear end has passed clear of the guide rail 186. The end of the latter is, however, sufficiently separated from the lower dog 203 to release the tongue 189 just before the door 151 is squarely in front of the chamber (Fig. 2). When in this position the springs 172 as before noted hold the door 151 a little away from the front of the retort as shown in Figs. 4 and 5. The rock shafts 208 and 202 (Figs. 5 and 6) have secured to their outer ends arms 212 and 213 to the outer ends of which are pivoted connecting rods 216 and 217. The other ends of the connecting rods are held between the two disks 220 and 221 by pivots 219 and 225 located on opposite sides of the disk center forming a peculiar knuckle joint or toggle joint connection. The disks are pivoted by their central shaft 222 to a pair of links 223 whose other ends are pivoted on a bracket 224 secured to the front tie bar 28, so as to provide a "floating" support for the toggle, whereby the latter automatically divides the force of its push equally upon the shafts 202 and 208. The outer disk 221 is furnished with a lever 227 having a handle 228 on its free end. By swinging the lever 227 over towards the front of the retort from the position shown in Fig. 5 to that shown in Fig. 1, the two shafts 208 and 202 are rocked in a direction to carry the two dogs 203 and 209 towards the mouth of the retort, thus forcing the door 151 and its gasket against its seat around the mouth of the retort, so as to effectually seal the entrance thereto. This method of suspending the door, and this arrangement of the toggle and its connections therewith, constitute an articulation by means of which the strains are automatically distributed evenly, so as to exert the same amount of pressure at the top and bottom of the door. In this arrangement, the weight of the lever 227 and its connections with the shafts 202 and 208 tend to press the door inwardly at the bottom and outwardly at the top; and in order to correct this tendency those parts should be counterweighted or counterbalanced. In the present instance this is accomplished by means of the spring 236 attached at one end to the lower arm 213 and at the other end to the tie bar 28.

On account of variations in the mechanism, and in the thickness of different gaskets, as well as in the thickness of the same gasket due to repeated compressions, means are provided for adjusting the parts so as to secure the desired amount of pressure when the toggle is in its door-closing position shown in Fig. 1. In that position the connecting rod 208 pivots 219 and 225 are preferably carried slightly past their dead centers, so that the pressure upon the rod tends to turn the lever 227 still further toward the front, this tendency being met by the stop pin 233 in the arm 232 appurtenant to the inner disk 220,

which stop pin engages the upright post 177 as shown in Fig. 1, to prevent any further movement toward the left of the lever 227 when the latter is in its locked or left hand position.

70

In order to further distribute the pressure uniformly upon the joint between the door and the retort, the pressure is transmitted to the door by means of the brackets 159 and 168 (see Fig. 6), the central portions of which are engaged by the dogs 209 and 203 respectively. Those brackets are secured to the door 151 at their ends only, clearances or recesses 163 and 170 being formed between the ends so that the central part of each bracket is not in contact with the door. This arrangement enables the pressure of the dogs 203 and 209 to be exerted against the door at four separated spots 164, 164 and 171, 171. The links 216 from which the door is suspended are preferably so located that they hang approximately perpendicular when the door is locked, thus carrying it squarely against its seat, in a direction substantially at right angles to the planes of the meeting surfaces.

85

The exit and entrance of the air for the exhausting and sealing operations are controlled by a valve comprising a tapered plug 254 (Fig. 4) fitted into a casing 252 which rests upon the base 272 secured to the left-hand leg 27 of the retort by means of the bracket 253. Four openings or ports 255, 256, 257, 258 lead through the casing. Into the port 255 is fitted the pipe 251 which leads to the exhaust pump. Into the port 256 is fitted the pipe 264 leading to the presser chamber 112 by means of the unions 267 and 268, flange 269 and pipe 137 (Fig. 7). Into the port 257 is fitted the pipe 263 leading to the jar chamber 33. The port 258 connects with the atmosphere through the valve base 272 (Fig. 4), which is made hollow and has a cover 273 hinged to its under side by means of the pin 274 (Fig. 3). The cover is held up in place by the head of the T bolt 280 which supports its outer edge by means of the notched ear 281 (Fig. 1), the body of the bolt 280 being fitted to swivel in the valve base 272 so that a half turn of the bolt releases the cover by permitting the notched ear to pass by the T head. The cover 273 is provided with a piece of wire gauze 276 or other suitable material which serves to exclude dirt and other foreign matter from entering the valve.

110

The plug 254 (Fig. 7) has four ports 285, 286, 287 and 288 which meet at a common center; and there are four positions which the plug 254 assumes relative to its casing 252. These positions are designated A, B, C and D, and are shown in Figs. 7, 8, 9 and 4, respectively. Position A (Fig. 7) is the regular exhausting position of the valve, and when in this position the port 285 coincides

115

120

125

130

with the port 255, the port 287 coincides with the port 256, the port 288 coincides with the port 257, while the port 258 is closed. The air exhausts from the jar chamber 33 through the pipes 263, to the pipe 251 which leads to the exhaust pump. The air also exhausts from the presser chamber 112, through the pipes 137 and 264 to the pipe 251.

In position B (Fig. 8) after a proper degree 10 of vacuum has been obtained, air is readmitted to the presser chamber 112 while being still excluded from the jar chamber 33. In this position the port 256 coincides with the port 286 and the port 288 coincides with the 15 port 258, while the ports 257 and 255 are closed. The air passes through the pipes 264 and 137 to the presser chamber 112, and is thus permitted to force the presser pistons 130 and 131 down upon the jar caps G (Fig. 20 11) as the vacuum is still retained in the jar chamber 33, and in that part of the cylinder chamber 123 which is below the piston 130.

In position C (Fig. 9) air is admitted to the 25 jar chamber 33 as well as to the presser chamber 112. In this position the port 285 coincides with the port 256, the port 287 coincides with the port 257, while the port 288 still coincides with the port 258, the former port being made with a wide opening in order 30 to keep it in coincidence with the port 258 during the movement of the plug 254 from position B to position C. The air passes to the jar chamber through the ports 258, 288, 287 and 257 and the pipe 263.

35 In position D (Fig. 4) the air exhausts only from the presser chamber 112, without exhausting from the jar chamber 33. This causes the air pressure in the jar chamber to lift any of the pairs of presser pistons 130 and 40 131 which may have failed to return to their upper positions through the action of the springs 132. The ports 257 and 258 are now closed while the ports 256 and 255 are in communication through the ports 288 and 287, 45 these connecting ports of the valve and the casing overlapping each other in this position to a limited extent only, as the small amount of exhaustion required necessitates but a small passage.

50 The plug 254 is moved from one position to another by means of a lever 292 (Fig. 1) secured to the stem 294 of the plug and having a handle 293 on its outer end. A latch 297 is pivoted on the lever 292 by the bolt 298 and carries on its outer end a handle 299. The inner end of the latch forms a pawl 300, which rides on the edge of an indexing plate 301. The latter is secured to the valve base 272, and has a hole in its center through 55 which the plug stem 294 passes. The edge of the plate 301 is in the contour of a number of concentric arcs, upon which the pawl 300 rests, and these arc portions terminate in peripheral shoulders A, B, C and D which, by 60 65 engaging the end of the pawl 300 arrest the

movement of the plug and indicate its position with reference to the ports of the casing, each position A, B, C or D of the valve being determined by bringing the pawl against the correspondingly lettered shoulder on the periphery of the plate. A spring 307 keeps the pawl in engagement with the plate except when it is drawn back by the handle 299. By this arrangement the valve is easily operated by the lever 292 so as to move it from 70 one position to another almost instantly and with the absolute certainty of arresting the movement when the valve reaches the position desired. The arrangement possesses the further advantage of always visibly indicating the exact position of the valve.

In order to permit the presser carriage 102 to be removed from the retort for examination or repairs, a pair of tracks 326 (Figs. 15 and 16) are secured to the turn table cross bars 38, 39, 40 and 41. A pair of removable tracks 327 are provided to extend from the inner ends of the tracks 326 to the outer ends of the tracks 101 in the bottom of the jar chamber 33, the tracks 327 being supported 85 by the bar 39 and the jar chamber floor 32. These removable tracks 327 are placed in position only when it is desired to withdraw the presser carriage 102 from the jar chamber, at which time they serve to support the carriage 102 between the retort and the turn table legs so it can be rolled on the wheels 103 from the jar chamber 33 to the tracks 326. The turn table is first removed, and the union 268 unscrewed, thus permitting the release of the pipe 137. The presser carriage with all its parts is thus readily accessible whenever occasion demands it. For convenience in manufacture the casing 111 of the presser chamber may be made in two or more 90 sections connected as shown in Fig. 16, by 95 means of an air pipe 331.

The consecutive operation of the parts in sealing a set of jars is as follows: The packed jars J with their caps and gaskets in position 100 are loaded upon the trays 33, after which the levelers 94 are placed on the caps. The trays are now placed upon the slide 78, which is assumed to be before the open end of the retort 26 and in alignment with the jar chamber 33. Also, the door 151 is assumed to be one side of the retort opening as shown in Fig. 3, and the valve 254 is assumed to be position D, Fig. 4. The slide 78 is now pushed on the rollers 56 into the chamber 33 110 over the roller 106, the side guidas 53 guiding it to enter properly between the base sides 105 (Fig. 14). The movement of the slide 78 is continued until the forward end is against the stop 110, at which time each jar 115 J will be under one of the presser pistons 131. The door 151 is now rolled on the track 152 up to the stop 193, the tongues 190 and 189 passing into the grooves of the two locking dogs 209 and 203, respectively (Figs. 2 and 120 130

6

5). During the movement the door is kept from contact with the flange 34 by the springs 172 and the guide rail 186. The door being now squarely in front of the open end of the retort, the lever 227 is swung forward by means of the handle 228, thus swinging the grooved ends of the two locking dogs 209 and 203 towards the retort, carrying with them the door tongues 190 and 189 thus 10 swinging the door 151 on the suspending links 160 and forcing it squarely against the front flange 34 of the retort, the gasket 157 insuring an air tight closure. The valve lever 292 is now moved to position A, 15 Figs. 1 and 7, the pawl end 300 stopping against the shoulder A. The air now exhausts from the jar chamber 33 through the pipe 263 and from the presser chamber 112 through the pipes 137 and 264. As soon as 20 the proper degree of vacuum has been obtained, the valve is moved to position B (Fig. 8) the movement being arrested at the proper point by the pawl end 300 encountering the shoulder B. The air enters through 25 the opening in the valve base 272 whence it passes through the pipes 264 and 137 to the presser chamber 112 (Fig. 10) where it acts on the presser pistons 130; through the ducts 135, on the presser pistons 131, as the 30 vacuum still exists below each piston. All the pistons are thus driven downward (Fig. 11) upon their respective jar caps G, with a degree of pressure much in excess of that of the ordinary atmospheric pressure, this excess depending on the degree of vacuum obtained, and on the combined pressure area of the two pistons 130 and 131 relative to the pressure area of the cap G. The valve is then moved to position C (Fig. 9) the pawl 40 end 300 being raised by the lever 297 to clear the shoulder B and riding over the periphery of the plate 301 till arrested by the shoulder C. In this position air is admitted to the jar chamber 33 through the valve base 272, 45 and the pipe 263, the presser chamber 112 being still in communication with the atmosphere but through the port 285 instead of the port 286. The caps G being already forced down upon the jars by the presser pistons 50 130 and 131, no air can enter the jars through their closure joints. As the pressure exerted by the pistons 130 and 131 is gradually relaxed through the equalizing of the pressure on both sides of the pistons, the 55 springs 132 return the pistons to their upper positions, and the atmospheric pressure retains the caps G in their pushed down position. The valve is now turned to position D (Fig. 4) thus permitting the presser chamber 60 112 to exhaust through the valve ports 288 and 287. This reduces the atmospheric pressure on the upper sides of the pistons, and if it happens that any of the pistons have failed for any reason to return to the upper position 65 the atmospheric pressure on their under

sides will at once force them to do so. The jars being now sealed, the door 151 is released by throwing the lever 227 back to its original position (Fig. 5), the action of the dogs 203 and 209 drawing the door away 70 from the flange 34 of the retort. The door is now rolled back against the stop 194 to the position shown in Fig. 3. The slide 78 with its load of sealed jars is then drawn out of the jar chamber 33 on to the rollers 56 and 75 up against the stops 80. The latch 64 is then turned downward carrying with it the latch 65 until both latches rest in the position shown in Fig. 16 with their tails 66 and 67 in alignment with the lugs 60. The turn 80 table is now swung around until its other end is between the latches 64 and 65 which are then turned up to keep it in that position, the other slide 78 being now in alignment 85 with the jar chamber 33. This other slide has received its load of jars during the sealing of the previous load on the other slide, and may now be pushed into the jar chamber and the sealing process allowed to proceed as before. 90

In order to adapt the apparatus for sealing jars of various heights, fillers 341, (Figs. 17 and 18,) of suitable height may be employed. The filler 341 is of the proper size to fit the slide top plate 78, the upturned edges of 95 which keep it in position. The filler is provided with a top plate 342 having upturned edges similar to the slide top 78, and these edges serve to hold the tray bottoms 83 in place. By the use of such fillers the caps H 100 of short jars K are raised to the proper level for bringing them to a suitable height under the pressers 131.

It is desirable in apparatus of this character to arrange the jars as close together as 105 possible in order to get as many of them as possible into a given space, thus reducing as far as possible the space which must be exhausted in order to seal a given number of jars. In the present arrangement, both the 110 desired compactness of arrangement and the augmented pressure are secured, by employing a plurality of pistons for each jar, placing them one above the other in tandem arrangement. This enables the jars to be placed 115 closely together in trays, while still employing a pressure which may be two or more times the ultimate pressure of the atmosphere upon the cap.

The shoulder B on the plate 301 is so disposed with reference to the shoulders A and C that the pawl 300 when being moved from the shoulder A to the shoulder C cannot be made to pass the shoulder B without being first lifted by the handle 299 against the 120 action of the spring 307. This requires a definite effort on the part of the operator and therefore causes a delay in the movement of the valve from the exhausting position A to the sealing position C. This delay occurs 125 130,

when the presser chamber is in communication with the atmosphere and while the jar chamber is still cut off therefrom; thus insuring the downward movement of the 5 pressers and the consequent sealing of the closure joint before any air can enter around that joint.

The functions of the springs herein shown may be performed by means of suitably arranged weights and levers. The shaft 222 may be mounted to slide vertically in a slot or any other convenient form of guide, the object being to suspend or sustain this central portion of the toggle connection against 15 lateral movement, while permitting its vertical floating movement, and its central portion is preferably maintained as herein shown, substantially in alinement with the opposite ends of the toggle connections.

20 The terms "upper," "lower," and similar terms denoting relative position are herein used in their relative and not their absolute sense, inasmuch as many of the parts may be reversed, inverted or transposed in many 25 ways that will be obvious to the mechanic or designer. The mechanism herein shown and described may be modified as to dimensions, amplitude of movement and in many other obvious ways to suit various requirements and different conditions of service.

We claim as our invention:—

1. In a jar sealing apparatus, the combination of a jar chamber, a plurality of jar carrying slides, and a table provided with 35 guideways for the slides, and mounted to carry the slides transversely, whereby they are successively carried into horizontal alinement with the jar chamber to permit them to be transferred horizontally from the table 40 to the chamber.

2. In a jar sealing apparatus, the combination of a jar chamber, a plurality of jar carrying slides and a turn table provided with a guideway for each of the slides, the 45 turn table being pivoted at one side of the center of the pathway of the said slides, whereby the slides may be brought successively into horizontal alinement with the jar chamber.

50 3. In a jar sealing apparatus, the combination of a jar chamber, a plurality of jar carrying slides, a turn table provided with a guide for each slide, and a pivotal support for the turntable located between the guideways, and at one side of the center line of the 55 jar chamber, whereby the slides are by rotation of the table carried successively into horizontal alinement with the jar chamber.

4. In jar sealing apparatus, the combination of a jar chamber, a pair of jar carrying slides, a turntable for supporting one of the slides in alinement with the jar chamber, and supporting the other slide in position to be brought into similar alinement by swinging 65 the turntable, means for locking the turn-

table when either slide is in alinement with the jar chamber, and stops for stopping the movement of the slides when they are drawn out of the jar chamber.

5. In jar sealing apparatus, the combination of a jar chamber, a door for hermetically sealing the jar chamber, a jar carrying slide, guide-ways for supporting and guiding the slide through the doorway into the jar chamber, jar holding trays supported by the slide, 75 and suitable filling pieces resting upon the bottom of the slide, and supporting the trays, to raise the tops of jars of different heights to a predetermined level.

6. In jar sealing apparatus, the combination of a jar chamber, a pair of jar carrying slides, rollers on which the slides rest, and a turntable for carrying the rollers and supporting one of the slides in alinement with the jar chamber while supporting the other 85 slide in position to be brought into similar alinement by swinging the turntable.

7. In jar sealing apparatus, the combination of a jar chamber, a pair of jar-carrying slides, a turntable for supporting one of the 90 slides in alinement with the jar chamber and for supporting the other slide in position to be brought into similar alinement by swinging the turntable, and side guides on the turntable to keep the moving slides in alinement with the jar chamber.

8. In jar sealing apparatus, the combination of a jar chamber, a door carriage, a door suspended from the carriage, and springs to yieldingly hold the door away from the jar 100 chamber.

9. In jar sealing apparatus, the combination of a jar chamber, a door carriage, a door suspended from the carriage, springs tending to hold the top of the door out of contact 105 with the jar chamber, and a guide rail parallel to the path of the door to confine the bottom.

10. In jar sealing apparatus, door mechanism therefor, having in combination a door 110 for hermetically closing the jar sealing chamber, toggle mechanism acting upon different portions of the door, and a floating support for the toggle mechanism for substantially equalizing its pressure upon the different 115 portions of the door.

11. In jar sealing apparatus, the combination of a jar chamber, a door, clamping devices operating on different portions of the door, and means including an equalizing 120 toggle device for distributing the clamping pressure on the different portions of the door.

12. In jar sealing apparatus, door mechanism therefor having in combination a door for hermetically closing the jar sealing chamber 125 of the apparatus, toggle mechanism acting in different directions upon different portions of the door, and a floating support for the toggle mechanism, located between the opposing portions thereof, for distributing the pressure 130

of the toggle mechanism with substantial equality upon the different portions of the door.

13. In jar sealing apparatus, door mechanism therefor, having in combination a door for hermetically closing the jar sealing chamber of the apparatus, toggle devices acting in opposite directions from a common center, upon different portions of the door, and a floating support for the toggle device mounted to yield substantially in the line of the opposing pressures to substantially equalize them.

14. In jar sealing apparatus, the combination of a jar chamber, a door carriage, a door supported by the carriage, and means including a toggle-joint device for clamping the door against the jar chamber.

15. In jar sealing apparatus, the combination of a jar chamber, a door carriage, a door supported by the carriage, and means including an adjustable toggle-joint device for clamping the door against the jar chamber.

16. In jar sealing apparatus, the combination of a jar chamber, a door carriage, a door supported by the carriage, and means including two toggle-joint devices acting from a common center for clamping the door against the jar chamber.

17. In jar sealing apparatus, the combination of a jar chamber, a door carriage, a door supported by the carriage, and means including two toggle-joint devices acting from a pivotally supported common center for clamping the door against the jar chamber.

18. In jar sealing apparatus, the combination of a jar chamber, a door carriage, a door supported by the carriage, means including two toggle-joint devices acting from a common center for clamping the door against the jar chamber, and means for supporting the said center for equalizing movement.

19. In jar sealing apparatus, the combination of a jar chamber, a door carriage, a door supported by the carriage, dogs engaging the door, and means for moving the dogs to clamp the door against the jar chamber.

20. In jar sealing apparatus, the combination of a jar chamber, a door carriage, a door supported by the carriage, dogs engaging with the door, and a toggle-joint device for moving the dogs to clamp the door against the jar chamber.

21. In jar sealing apparatus, the combination of a jar chamber, a door carriage, a door for the jar chamber supported by the carriage, dogs engaging with the door, and two toggle joint devices which act on the dogs from a common center to clamp the door against the jar chamber.

22. In jar sealing apparatus, the combination of a jar chamber, a door carriage, a door supported by the carriage, dogs engaging with the door, two toggle-joint devices which

act on the dogs from a common center to clamp the door against the jar chamber, and means for supporting the common center for equalizing movement.

23. In jar sealing apparatus, the combination of a jar chamber, a door carriage, a door supported by the carriage, dogs engaging with the door, and two toggle-joint devices which act on the dogs from a pivotally supported common center, to clamp the door against the jar chamber.

24. In jar sealing apparatus, the combination of a jar chamber, a door carriage, a door supported by the carriage, dogs engaging with the door, two toggle-joint devices which act on the dogs from a common center to clamp the door against the jar chamber, and a lever for operating the toggle-joint devices.

25. In jar sealing apparatus, the combination of a jar chamber, a door carriage, a door supported by the carriage, dogs engaging with the door, two toggle-joint devices which act on the dogs from a common center to clamp the door against the jar chamber, and counterbalancing means for the weight of the toggle-joint devices.

26. In jar sealing apparatus, the combination of a jar chamber, a door carriage, a door for the jar chamber supported by the carriage, dogs engaging with the door, two toggle-joint devices which act on the dogs from a common center to clamp the door against the jar chamber, and adjusting means for the toggle-joint devices and their connected parts.

27. In jar sealing apparatus, the combination of a jar chamber, a door carriage, a door supported by the carriage, two toggle-joint devices and connections acting on the dogs from a common center, and means for varying the length of the connections.

28. In jar sealing apparatus, the combination of a jar chamber and a sealing carriage, removably contained within the jar chamber, comprising a base and a presser chamber provided with a plurality of independently movable pressers operated by atmospheric pressure.

29. In jar sealing apparatus, the combination of a jar chamber, a plurality of independently-movable jar pressers, a carriage removably contained within the jar chamber, and having the jar pressers attached thereto, and fluid-pressure actuated means for operating the pressers.

30. In jar sealing apparatus, the combination of a jar chamber, a plurality of independently-movable jar-pressers, a carriage removably contained within the jar chamber and having the jar pressers attached thereto, and an inclined cap-leveling surface adjacent to the pressers, to level the individual caps as they are moved toward the pressers.

31. In jar sealing apparatus, the combina-

- tion of a jar chamber and a sealing carriage removably contained within the jar chamber, and comprising a base and a presser chamber having attached thereto independently 65 movable jar-pressers operated by atmospheric pressure, and a cap-leveling device located near the front of the presser chamber to level the caps as they are moved toward the pressers.
- 10 32. In jar sealing apparatus, the combination of a jar chamber, a sealing carriage removably contained within the jar chamber, and comprising a base and a presser chamber provided with a plurality of independently 70 movable jar-pressers operated by atmospheric pressure, and means for connecting the presser chamber to exhausting apparatus.
- 15 33. In vacuum sealing apparatus, a valve having an exhaust port 255, an atmosphere port 258, and two chamber ports 256 and 257, said valve being provided with means for closing the exhaust port and the atmosphere port independently of each other, and for 75 connecting the two chamber ports either with the exhaust port or with the atmosphere port.
- 20 34. In vacuum sealing apparatus, a valve having an exhaust port 255, an atmosphere port 258, and two chamber ports 256 and 257, said valve being provided with means for closing the exhaust port and the atmosphere port independently of each other, and for 80 connecting the two chamber ports either with the exhaust port or with the atmosphere port, said means being adapted also to connect the chamber port 256 either with the exhaust port or with the atmosphere port while keeping the other chamber port 85 closed.
- 25 35. In vacuum sealing apparatus, the combination with a valve having an exhaust port, an atmosphere port and two chamber ports, of means for bringing the ports into proper coincidence and means for arresting the operating movements at predetermined 90 positions.
- 30 36. In vacuum sealing apparatus, the combination with a valve having an exhaust port, an atmosphere port and two chamber ports, of means for bringing the ports into proper coincidence, and means for limiting the valve-operating movement in both directions and for arresting it at predetermined 95 intermediate positions.
- 35 37. In jar sealing apparatus, the combination of a jar chamber, a presser chamber, a valve, a passage connecting the valve to the jar chamber, a passage connecting the valve to the presser chamber, a passage connecting the valve to an exhausting apparatus, a passage connecting the valve to the atmosphere, means for operating the valve to close the exhaust passage and the atmosphere passage 100 independently of each other and to connect the two chamber passages either with the exhaust passage or with the atmosphere passage, said means being adapted also to connect the presser chamber passage either with the exhaust passage or with the atmosphere passage while keeping the jar chamber passage closed.
- 40 38. In jar sealing apparatus, the combination of a jar chamber, a presser chamber, a valve, a passage connecting the valve to the jar chamber, a passage connecting the valve to the presser chamber, a passage connecting the valve to an exhausting apparatus, a passage connecting the valve to the atmosphere, means for operating the valve to close the exhaust passage and the atmosphere passage 105 independently of each other and to connect the two chamber passages either with the exhaust passage or with the atmosphere passage, said means being adapted also to connect the presser chamber passage either with the exhaust passage or with the atmosphere passage while keeping the jar chamber passage closed.
- 45 39. In jar sealing apparatus, the combination of a jar chamber, a presser chamber, a valve, a passage connecting the valve to the jar chamber, a passage connecting the valve to the presser chamber, a passage connecting the valve to an exhausting apparatus, a passage connecting the valve to the atmosphere, means for operating the valve to bring the 110 passages into proper coincidence, and means for arresting the valve operating movement at predetermined positions.
- 50 40. In jar sealing apparatus, the combination of a jar chamber, a presser chamber, a valve, a passage connecting the valve to the jar chamber, a passage connecting the valve to the presser chamber, a passage connecting the valve to an exhausting apparatus, a passage connecting the valve to the atmosphere, means for operating the valve to bring the 115 passages into proper coincidence, and means for limiting the valve operating movement in both directions and for arresting it at predetermined intermediate positions.
- 55 41. In jar sealing apparatus, the combination of a jar chamber, a presser chamber, a passage for connecting with air exhausting apparatus, a valve comprising a plug and a casing, a lever to oscillate the plug, a latch connected with the lever, and a peripherally-shouldered plate to coöperate with the latch 120 in limiting the oscillation of the plug in both directions and to arrest the movement of the plug at predetermined intermediate points.
- 60 42. In vacuum sealing apparatus, the combination of a jar chamber, a presser chamber, 125 passages connecting with means for exhausting both chambers, and means for readmitting air independently to the two chambers.
- 65 43. In vacuum sealing apparatus, the combination of a jar chamber, a presser chamber, passages connecting with means for exhausting both chambers, an air inlet and a valve provided with connections leading independ-

ently to the two chambers, whereby air may be admitted to one chamber without admitting it to the other chamber.

44. In vacuum sealing apparatus, the combination of a jar chamber, a presser chamber, passages connecting with means for exhausting both chambers, and an air inlet valve provided with independent connections to the two chambers and adapted to admit the

10 air through one connection in advance of admitting it to the other connection.

45. In vacuum sealing apparatus, the combination of a jar chamber, a presser chamber, passages connecting with means for exhausting 15 the chambers, and means including a valve having a plurality of ports for readmitting air independently to the two chambers.

46. In vacuum sealing apparatus, the combination of a jar chamber, a presser chamber, 20 an air inlet valve having independent air connections to the two chambers, the valve being provided with a plurality of ports for admitting the air first to one chamber and then 25 to the other chamber.

47. In vacuum sealing apparatus, the combination with a valve having an air inlet, a connection with exhausting apparatus, and a plurality of connections to be served by the 30 said inlet and exhaust connections, the valve being provided with ports for connecting either the exhaust or the inlet with one or both of the said plural connections.

48. In vacuum sealing apparatus, the combination of a valve provided with an air inlet, 35 an exhaust outlet and a plurality of connections to be served by the said inlet and exhaust, the valve being provided with ports for connecting the air inlet and the exhaust 40 outlet independently of each other, with one or both of the said plural connections.

49. In vacuum sealing apparatus, the combination of a valve provided with an air inlet, 45 an exhaust outlet, and a plurality of connections to be served by the said inlet and exhaust, the valve being provided with ports, which as the valve is operated first connects the exhaust outlet with the plural connections, and then connects the air inlet first 50 with one, and then with the other of said plural connections.

50. In vacuum sealing apparatus, the combination of a valve casing having four connections disposed at substantial right angles 55 with each other, and a valve plug provided with four ports communicating with the said connections, substantially as described, whereby one of the said connections may be put in communication simultaneously with a 60 plurality of the other connections, and whereby another set of connections may be put in communication with the two first named connections, one after the other.

51. In a jar sealing apparatus, the combination of a jar chamber and pneumatic pres-

sure sealing apparatus mounted for traveling movement into and out of the jar chamber.

52. In jar sealing apparatus, the combination of a jar chamber, pneumatic sealing apparatus mounted for traveling movement 70 into and out of the chamber, and means for connecting the said apparatus with its pneumatic operating means when in position in the chamber.

53. In jar sealing apparatus, the combination of a chamber pneumatic sealing apparatus, a carriage on which the said apparatus is mounted for traveling movement into and out of the chamber, and means for establishing pneumatic connection with the said apparatus through the wall of the chamber 80 when the said apparatus is within the chamber.

54. In jar sealing apparatus, the combination of a chamber, pneumatic pressure sealing apparatus mounted for traveling movement into and out of the chamber, and ways for guiding and supporting the said apparatus for its traveling movement into and out of the chamber.

55. In jar sealing apparatus, the combination of a chamber, pneumatic sealing apparatus mounted for traveling movement into and out of the chamber, means for establishing pneumatic connection with the said apparatus through the wall of the chamber when the apparatus is within the chamber, and ways for guiding and supporting the said apparatus for its traveling movement into and out of the chamber.

56. In jar sealing apparatus, the combination of pneumatic pressure sealing apparatus mounted for traveling movement into and out of the chamber, means external to the chamber for supporting and guiding the jars to and from the chamber, provided also with ways for guiding and supporting the sealing apparatus in its travel to and from the chamber.

57. In jar sealing apparatus, the combination of a chamber, pneumatic pressure sealing apparatus mounted for traveling movement into and out of the chamber, means including a turntable for supporting and guiding the jars while being transferred to and from the chamber, provided also with ways for supporting and guiding the jar sealing apparatus in its traveling movement from and to the chamber.

58. In jar sealing apparatus, the combination of a chamber, a frame external to the chamber provided with a turntable for supporting the jars while being transferred to and from the chamber, the frame being also provided with ways for guiding and supporting the jar sealing apparatus during its traveling movement into and out of the chamber.

59. In jar sealing apparatus, the combination of a chamber, pneumatic pressure

- sealing apparatus mounted for traveling movement into and out of the chamber, a frame external to the chamber provided with a removable turntable to facilitate 5 transferring the jars to and from the chamber, and having also ways for supporting and guiding the jar sealing apparatus while the latter is being moved out of and into the chamber.
- 10 60. In jar sealing apparatus, door mechanism therefor, having in combination a door carriage mounted to travel in the general direction of the plane of the door, a door mounted on the carriage for movement toward and from the plane of the door seat, and a guide rail for holding the door away from the plane of its seat during the movements of the carriage.
- 15 61. In jar sealing apparatus, door mechanism therefor, having in combination a door carriage mounted to travel in the general direction of the plane of the door, a door mounted on the carriage for movement toward and from the plane of the door seat, and a guiding rail for holding the door away from the plane of its seat during the travel 20 of the carriage, the guiding engagement between the rail and the door being discontinued when the door stands opposite its 25 seat.
62. In jar sealing apparatus, door mechanism therefor having in combination a door carriage mounted to travel in the general direction of the plane of the door, a door mounted on the carriage for movement toward and from the plane of its seat, a dog for moving the door toward and from its seat, and a rail for guiding the door to hold its sealing face in a plane away from the plane of its seat, during the travel of the carriage. 30
63. In jar sealing apparatus, door mechanism therefor having in combination a door carriage mounted to travel in the general direction of the plane of the door, a door suspended on the carriage for swinging movement toward and from the plane of its sealing seat, dogs for moving the door toward and from its sealing seat, and a guide rail engaging with the door during its travel with the carriage to hold the sealing face of the door at one side of or away from the plane of the sealing seat. 40
